UNITED STATES PATENT OFFICE.

WILLIE E. LACEY, OF ROYAL, IOWA.

STARTER-PAWL TRIPPER FOR MAGNETOS.

Application filed May 8, 1925. Serial No. 28,815.

To all whom it may concern:

Be it known that I, WILLIE E. LACEY, a citizen of the United States, residing at Royal, in the county of Clay and State of Iowa, have invented a certain new and useful Starter-Pawl Tripper for Magnetos, of which the following is a specification.

The object of my invention is to provide a starter pawl tripper for magnetos of simple, 10 durable and inexpensive construction.

Another object is to provide means for operating my tripper mechanism.

Still a further object is to provide a means, operable from the spark control lever, whereby my trip will be automatically operated in conjunction with said lever.

Still a further object is to provide means whereby my trip mechanism will be automatically rendered inoperative when the 20 driving range of the spark control lever is reached.

With these and other objects in view, my invention consists in the construction, arrangement and combination of the various 25 parts of my device, whereby the objects contemplated are attained, as hereinafter more fully set forth, pointed out in my claims, and illustrated in the accompanying drawings, in which:

30 Figure 1 is an elevation of my tripper as attached to a tractor showing its relation thereto.

Figure 2 is a view of the tripper taken on the line 2—2 of Figure 1.

35 Figure 3 is a sectional view on the line 3—3 of Figure 2.

Figure 4 is a sectional view on the line 4—4 of Figure 3.

40 Figure 5 is a sectional view on the line 5—5 of Figure 1;

Figure 6 is a perspective view of the bar for operatively connecting parts of my tripper to the spark control rod of the tractor.

On the accompanying drawing, I have 45 used the reference numeral 10 to indicate a tractor. For furnishing the spark for exploding the charge in the cylinders, a magneto 11 is usually provided.

50 In large tractors, such as a McCormick-Deering as illustrated, it is difficult, when starting, to rotate the crankshaft fast enough to get a spark from the magneto 11 which is strong enough to explode the gas mixture in the cylinders. For this reason, large 55 tractors have an "impulse starter" type of magneto.

In operation, the driver of the tractor, before starting, engages the stud 12 of the starter pawl 13 with his finger and moves it from the position in Figure 2 to the position 60 in Figure 4. The pawl 13 is held either against the stop 14 or the periphery of the disk 18 by a spring 15 of the "over center" type. The spring 15 is held in position on a rod 16, which passes through a hole in the 65 bracket 17 attached to the magneto.

In Figure 2, the pawl 13 is shown in disengaged position while in Figure 4, it is shown in position for engaging the notch 19 of the disc 18 and thereby causing the "impulse" action. This action, I will not describe, because it forms no part of my present invention and is common to impulse magnetos such as the Splitdorf.

This "impulse" action continues until the 75 engine has attained a speed of about 200 R. P. M. at which time the pawl 13 automatically assumes the position shown in Figure 2.

The foregoing is the ordinary tractor arrangement and it is always necessary to raise the hood each time the engine is started in order to trip the starting pawl as a severe back fire in the engine is the result of not so doing.

80 My invention consists in a device for automatically tripping the starting pawl 13 by manipulating the hand lever on the spark control tube 24. I have provided a bar 25 clamped by a U bolt 26 to the tube 24. 85

The bar 25 is clamped by a U bolt 28 to the lever 27 which is secured to the tube 24. A U bolt 29 clamps a short bushing 30 to the bar 25. The bushing 30 fits loosely around the carburetor control rod 31 and thereby permits the bar 25 to be moved simultaneously with the spark control tube 24 without affecting the adjustment of the carburetor control rod 31.

An extension 32 is provided on the bar 100 25 for operating my tripping mechanism.

Although I have illustrated a means of operating my device from the spark control rod of a tractor, it is to be understood that any mechanical equivalent may be substituted for the bar 25 or an independently operated control rod could be used for moving the bar 33.

When stopping an engine equipped with an "impulse starter" magneto, the spark 110 control lever on the dash is moved to fully retarded position which, "grounds" the mag-

neto, thereby stopping the spark. The means for grounding the spark is part of the magneto and is therefore not illustrated on the drawings. The position of the bar 33 when the magneto is grounded is illustrated in dotted lines in Figure 2.

In starting the engine, the spark control lever is advanced to proper starting position. In so doing, the shoulder 34 on the bar 33 engages the cross piece 35 of a pair of arms 36, due to the weight 37 which is secured to the bar 33 and causes its lower end 33^a to swing against the cross piece 35. The arms 36 are pivoted on a pin 36^a, which is supported by bars 36^b on the frame 47. This moves the arm 36 which is connected by a spring 38 to a bell crank 39. The bell crank 39 is pivoted to an ear 39^a on the frame 47 by a pin 39^b.

20 The bell crank 39 is connected by a link 40 to an arm 41.

From the foregoing, it will be seen that as the spark is advanced, the arms 36 are swung downward against the action of the spring 42, which swings the bell crank 39 and the arm 41 against the action of the spring 43. The spring 43 is hooked through a hole in the ear 43^a on the frame 47.

In this connection, it is well to mention that the spring 38 is much stronger than the spring 43 which is merely for the purpose of returning the parts to their initial position. The spring 42 is also for this purpose, which is connected to a pin 42^a on one of the arms 36 and to an ear 47^a on the frame 47.

The moving arm 41 engages the pin 12 on the starter pawl 13, and causes it to assume its engaging position for starting the engine. A plurality of holes is provided for each end of the link 40 so that my device can be adjusted to various magnetos or tractors.

45 A bell crank 44 pivoted to an ear 44^a by means of a pin 44^b, is connected to one of the arms 36 by a link 45. In Figure 4, the spark is not yet advanced sufficiently for normally running. Further movement of it will cause the end 46 to swing to the right and disengage the shoulder 34 from the cross piece 35. The tripper mechanism will then be brought back to initial position by the springs 42 and 43, and the bar 33 is free to move between the arms 36 through its entire driving range as illustrated in Figure 2.

60 A plurality of holes are provided in one of the arms 36 for the link 45 so that adjustment can be made for disengaging the shoulder 34 immediately after the pawl 13 is tripped and before the magneto is fully advanced to starting position.

If the arm 41 bears against the pin 12 before this disengagement occurs, the spring 65 38 compensates for the over movement of the

arms 36. The spring 38 is connected at 38^a to the bell crank 39 and at 38^b to one of the arms 36.

I have shown the frame 47 having an extension 48 which is bolted to the engine 70 block. An extension 49 spaces the lower end from the crank case, and an extension 50 bolts to the governor housing. These fastening devices can be modified for attachment to other types of tractors or engines. 75

It will be seen that I have provided a tripping device, which eliminates the necessity of raising the hood of the tractor and tripping the starting pawl by hand.

Having once been installed, the driver can 80 forget that he has an impulse starter, as it is tripped automatically by my device when he advances his spark. Retarding the spark when stopping and advancing it when starting are necessary operations, and my device 85 being operatively attached thereto, is therefore automatic.

Some changes may be made in the construction and arrangement of the various parts of my invention, without departing from the real spirit and purpose of my invention, and it is my intention to cover by my claims, any modified forms of structure or use of mechanical equivalents, which may be reasonably included within their 95 scope.

I claim as my invention:

1. In combination with an engine, equipped with an impulse starter magneto, means for tripping the starting pawl of said magneto, said means comprising a frame supported on said engine, an arm clamped to the spark control mechanism of said engine, a bar pivoted to said arm, a shoulder on said bar for engaging a lever pivoted to said frame whereby movement of said spark control mechanism will move said lever for engaging said starter pawl. 100

2. In combination with an engine, equipped with an impulse starter magneto, means for tripping the starting pawl of said magneto, said means comprising a frame supported on said engine, an arm clamped to the spark control mechanism of said engine, a bar pivoted to said arm, a shoulder on said bar for engaging a lever pivoted to said frame whereby movement of said spark control mechanism will move said lever for engaging said starter pawl, a bell crank pivoted on said frame and connected by a link to said lever, whereby said bell crank will disengage the shoulder of said bar from said lever at a predetermined position of said spark control mechanism. 110

3. In combination with an engine, equipped with an impulse starter magneto, means for tripping the starting pawl of said magneto, said means comprising a frame supported on said engine, an arm clamped to the spark control mechanism of said en- 125

- gine, a bar pivoted to said arm, a shoulder on said bar for engaging a lever pivoted to said frame whereby movement of the spark control mechanism will move said lever for engaging said starter pawl, a bell crank pivoted on said frame and connected by a link to said lever, whereby said bell crank will disengage the shoulder of said bar from said lever after said lever has engaged said 55
- 10 starter pawl at a predetermined position of said spark control mechanism.
4. In combination with an engine, equipped with an impulse starter magneto, means for tripping the starting pawl of said 60 magneto, said means comprising a frame supported on said engine, an arm clamped to the spark control mechanism of said engine, a bar pivoted to said arm, a shoulder on said bar for engaging a lever pivoted 65 to said frame, a bell crank pivoted to said frame having one end operatively connected to said lever and the other end operatively connected to a starting pawl engaging arm whereby said starting pawl engaging arm will be actuated upon movement of said 70 spark control mechanism.
5. In combination with an engine, equipped with an impulse starter magneto, means for tripping the starting pawl of 75 said magneto, said means comprising a frame supported on said engine, an arm clamped to the spark control mechanism of said engine, a bar pivoted to said arm, a shoulder on said bar for engaging a lever pivoted 80 to said frame, a bell crank pivoted to said frame having one end operatively connected to said lever and the other end operatively connected to a starting pawl engaging arm whereby said starting pawl engaging arm will be actuated upon movement of said spark control 85 mechanism, a second bell crank pivoted to said frame and operatively connected to said lever, and having an end adapted to force said shoulder on said bar from engagement with said lever after said starting pawl engaging arm has tripped said starting pawl.
6. In combination with an engine, equipped with an impulse starter magneto, means for tripping the starting pawl of 90 said magneto, said means comprising a frame supported on said engine, an arm clamped to the spark control mechanism of said engine, a bar pivoted to said arm, a shoulder on said bar for engaging a lever pivoted 95 to said frame, a weight on said bar for causing said engagement whereby movement of said spark control mechanism will move said lever for engaging said starter pawl, a bell crank pivoted on said frame and connected by a link to said lever whereby the bell crank will disengage the shoulder of said bar from said lever after said lever has engaged said starter pawl at a predetermined position of said spark 100 control mechanism.

Des Moines, Iowa, April 22, 1925.

WILLIE E. LACEY.
